United States Patent

Des. 239,654
Patented Apr. 20, 1976

239,654

RADIO

Donald J. Booty, Frankfort, Ill., assignor to
Amico, Inc., Philadelphia, Pa.

Filed Apr. 17, 1974, Ser. No. 461,679

Term of patent 14 years

Int. Cl. D14—03

U.S. Cl. D56—4 B

FIG. 1

FIG. 2

FIG. 3

FIG. 5

FIG. 4

FIG. 1 is a front elevational view of a radio showing my new design;

FIG. 2 is a right side elevational view, the left side being a mirror image thereof;

FIG. 3 is a top plan view;

FIG. 4 is a rear elevational view; and

FIG. 5 is a bottom plan view.

The ornamentation on the bottom two drawer fronts in FIG. 1 is flat.

I claim:

The ornamental design for a radio, substantially as shown and described.
